RECORDING DEVICE FOR RAILWAYS.

Application filed February 14, 1921. Serial No. 444,864.

To all whom it may concern:

Be it known that we, HEINRICH HEYN, residing at Datteln i. W., Germany, and FRIEDRICH ZIMMERMANN, residing at Essen, 5 Germany, both citizens of the Republic of Germany, have invented a certain new and useful Improvement in Recording Devices for Railways, of which the following is a specification.

10 This invention relates to a device suitable for railways and serving to record and indicate the axles running across a track. The present device differs from similar devices of the kind already known primarily by the 15 feature that it is adapted not only to record the number of axles and their running direction, but also the amount of the axle pressure and the precise time at which the said axles have run across a track equipped with 20 the recording device, so that the records obtained will, as said, not only comprise the number and running direction of the axles but also the amount of the pressure exerted by each axle and further the time at which 25 the particular section of the track entering into consideration was crossed.

The invention will be further described with reference to the accompanying drawings which show, by way of example, one 30 embodiment of the subject matter of the invention and in which:

Fig. 1 is a side elevation of the portion of the device arranged on one of the rails of a railway track,

35 Fig. 2 is a pertinent top view on an enlarged scale, Fig. 3 is a view, partly in section, of a portion of Fig. 1,

Fig. 4 is a cross section on line 4—4 in Fig. 3, looking from the right,

40 Fig. 5 is a cross section on line 5—5 in Fig. 3, seen from above,

Fig. 6 is a cross section on line 6—6 in Fig. 4, seen from above,

45 Fig. 7 is a cross section on line 7—7 in Fig. 4, looking from the left,

Fig. 8 is a cross section on line 8—8 in Fig. 3, seen from above,

Fig. 9 is a cross section on line 9—9 in Fig. 2,

50 Fig. 10 is a cross section on line 10—10 in Fig. 9, seen from above,

Fig. 11 is a diagram showing the system of electrical connections in conjunction with a recording mechanism, and

Fig. 12 shows one of the records made by 55 the recording mechanism.

The portion of the device which is arranged on one of the rails of a railway track will be described first.

On the web a^1 of the rail A belonging 60 to a track running to a railway station there are fixed two fish-plates B and B^1 (Figs. 1, 2, 3, 4 and 5). The fish-plate B^1 is provided in its middle portion with a flange b^2 (Fig. 4) projecting beyond the inner flange a^2 of the rail and immediately adjoining which there is arranged a cylindrical pot b^3 , suitably grounded. Within 65 said pot b^3 there is displaceably arranged a hollow cylinder C closed by a cover c^1 and subject to the action of a very powerful spring D tending to push it upwards. The displaceability of the hollow cylinder C is confined by two pins b^4 arranged at the pot b^3 and projecting each into a vertical groove c^2 (Fig. 4) formed in the hollow cylinder C. On the cover c^1 are cast 70 two upwardly directed eyes c^3 within which there is lodged to rotate a bolt E. To this bolt there are linked two one-armed levers 80 F and F^1 provided at their free ends with suitable longitudinal slots f^2 and f^3 (Fig. 5) and adapted to rock in the manner disclosed in Figs. 1 and 2 about pivots b^5 and b^6 fixed to the fish-plate B^1 . The surfaces 85 f^4 and f^5 (Fig. 2) of said levers and which extend in the direction of the rails are, from the pivots b^5 and b^6 , upwardly inclined and thus constitute contact faces for the flange g^1 of a wheel G running across 90 the rail A (Fig. 4). To the hollow cylinder C there is fixed an upright rack bar c^4 shiftable within a guide b^7 (Figs. 3 and 6) arranged on the pot b^3 , the teeth of this rack bar being disposed outside of the pot b^3 95 and adapted to gear with a pinion H (Figs. 3, 4 and 6). Said pinion H is adapted to rotate, by means of a hub h^1 rigidly connected to it, about a pivot b^8 fixed to the pot b^3 . The hub h^1 consists of electrically 100 non-conducting material and has a flange h^2 to which is fixed a downwardly extend-

ing lever h^3 . The lower portion h^4 of this lever h^3 is somewhat enlarged toward one side and possesses a L-shaped portion. Within this L-shaped portion h^4 there is fixed a pin h^5 introduced from below (Figs. 4, 6 and 7), the axis of which is located in parallel to the upright web of the part h^4 . On this pin h^5 there is arranged a prismatic element K, having the width of the part h^4 (see Fig. 7) and guided by the inside face of said upright web. The element K is acted upon by a spring h^1 (Fig. 7) wound about the upper, slightly stepped portion of the pin h^5 adapted to force the element K against the upper flange of the L-shaped portion h^4 . Within said element K there is a hole h^2 the axis of which intersects the axis of the pin h^5 at right angles. Within the hole h^2 there is shiftably disposed a pin M forming a contact member and acted upon by a spring m^1 , tending to constantly force the pin M out of the hole h^2 . The displaceability of the pin M is limited by a cap h^3 (Fig. 4) covering the hole h^2 , and through which the pin M projects with its stepped extremity. With said extremity projecting beyond the cap h^3 the pin M bears up against a plate b^9 having the shape of an annular sector and bolted up against the external wall of the pot b^3 in the manner illustrated in Figs. 3 and 6. Said plate b^9 consists of electrically non-conducting material and is provided on its flat surface b^{10} facing the pin M, with an arcuate edge b^{11} comprising an inclined surface b^{12} , a shoulder b^{13} leading to an intermediate step b^{14} and a shoulder b^{15} leading down again to the surface b^{10} (see Figs. 3, 4 and 8). Within the plate b^9 there are arranged two contact studs b^{16} and b^{17} , of which the one, b^{16} , is disposed in the step b^{14} , and the other, b^{17} , in the surface b^{10} . The shoulders b^{13} and b^{15} are disposed at an incline to the radii drawn from the centre to the contact studs b^{16} and b^{17} . All the parts arranged on the outer wall of the pot b^3 are suitably covered and protected by a box b^{18} into which a supply cable b^{19} consisting of four lines is introduced, the system of connection of which will be more fully explained hereinafter.

On the web a^1 of the rail A there are bolted at some distance remote from the fish-plates B and B^1 , two additional fish-plates N and N^1 (Figs. 1, 9 and 10). The fish-plate N¹ disposed on the inside of the rail A is provided with an upright pot n^2 supported by a flange n^3 on the inside flange a^2 of the rail A. Within this pot n^2 there is shiftably arranged a hollow cylinder P covered by a cap p^1 and acted upon by a spring p^2 which consequently tends to force it upward. In this case, too, the displaceability of the hollow cylinder P is suitably

confined by a pin n^4 projecting into a vertical slot p^3 formed in the hollow cylinder P. The cap p^1 is fitted with two bevelled surfaces p^4 and p^5 (Figs. 1 and 2) running in the direction on the rails and forming the contact faces for the flange g^1 of a wheel G running across the rail A (Fig. 9). On the underside of the cap p^1 there is fixed a plate p^6 of a non-conducting material and within which there are shiftably arranged two contact pins Q and Q^1 . Each of these contact pins Q and Q^1 , respectively, is acted upon by a spring q^2 in the manner disclosed in Fig. 9. Opposite to the contact pins Q and Q^1 there are disposed two contact members N^5 and N^6 fixed to the bottom of the pot n^2 by the aid of a non-conducting intermediate member n^7 . The contact members N^5 and N^6 are connected to electric lines r^4 forming together, outside of the pot n^2 , a cable n^8 (Fig. 9).

Within a chamber, say, for example, the station master's room, which is at a distance remote from the part of the device hitherto explained, there is arranged a recording drum R (Fig. 11) adapted to be jerkwise rotated by intervention of an electro-magnetically operated feed mechanism r^1 . The magnet winding r^2 of said feed mechanism is connected by lines r^3 and r^4 to a source of continuous current R^5 . Within the line r^4 are disposed the hereinbefore described contact member M arranged at the lever h^3 (see Figs. 3, 4, and 6) as also a point of break formed by the already mentioned contact members N^5 N^6 which point is adapted to be bridged by aid of a contact element comprising the mentioned contact pins Q and Q^1 (Fig. 9). Against the exterior of the recording drum R, fitted with a sheet of paper, there bears up a recording pen S fixed to a screw nut s^1 adapted to be displaced along a spindle T. This spindle T is driven by a clockwork T^1 . In addition, there are arranged to rock on the said screw nut s^1 two supplementary recording pens S^2 and S^3 which, normally do not make contact with the recording drum R but may be caused to do so by means of electromagnets. The magnet windings r^6 and r^7 of these latter electromagnets are connected in the manner disclosed in Fig. 11, on the one hand, by means of lines r^{11} and r^{27} , to points along line r^4 located between the magnet winding r^2 and the point of break N^5 N^6 to be bridged by the contact pins Q and Q^1 , while, on the other hand, they are connected by means of lines r^{20} and r^{28} with the contact studs b^{16} and b^{17} (see also Fig. 3) with which the contact member M arranged on the lever h^3 is adapted to make contact. (For the sake of convenience, the contact studs b^{16} and b^{17} are shown as disposed to the right and left of the lever h^3 in Fig. 11, whereas

in the construction described by way of example and shown in Fig. 4, they are both located to the left of the lever h^3).

In considering the manner of operation 5 of the device, let it now be assumed that the clockwork T^1 (Fig. 11) has been started at midnight and is revolving the spindle T with a uniform angular velocity. Hence, the screw nut s^1 will come to displace itself 10 at a uniform rate of speed in the direction indicated by the arrow x (Fig. 11) and the recording pen S will, starting at midnight, mark a straight line r^8 (Fig. 12) on the sheet covering the drum R , said line following 15 the direction of the axis of rotation of said drum, the marking of this line continuing from midnight right on to 2 a. m. At 2 a. m. there approaches a train running in the direction denoted by the arrow y (Fig. 20 1). As soon as the first wheel G (Fig. 9) of its engine comes to bear with its wheel flange g^1 down upon the contact faces p^4 and p^6 of the hollow cylinder P , this latter is forced down counter to the action of its 25 spring p^2 and the resilient pins Q and Q^1 make contact with the studs N^5 and N^6 . By the contact thus established, the circuit R^5 r^4 N^6 Q^1 Q N^5 r^4 r^2 r^3 R^5 will be closed and the magnet winding r^2 excited. As a result, 30 the appropriate electromagnet now sets the feed mechanism r^1 in operation and the recording drum R begins to revolve. The rotation of this drum continues only until the wheel G has departed from the contact face 35 p^5 , for as soon as this has been effected, the hollow cylinder P will, acting under the impulse of its spring p^2 , at once return into its upper end position as shown and in which the circuit above indicated is broken. While 40 the drum R is rotating the recording pen S marks a short line forming part of a straight line r^9 running in the peripheral direction of the drum R , i. e. at right angles to the straight line r^8 . After a very short 45 space of time, the said wheel G attains the contact face f^4 of the lever F and begins to rock this latter about the pivot b^5 . Owing to the rocking motion executed by the lever F , in which also the lever F^1 , is caused 50 to participate, the hollow cylinder C connected up to the levers F F^1 by the link E , c^3 is forced downwards counter to the action of the spring D . In the movement executed by the hollow cylinder C , the lever 55 h^3 rigidly connected to the pinion H is caused to participate by intervention of the rack gear c^4 H in such a manner that it will carry out a rocking motion in the direction denoted by the arrow z (Fig. 3). In the 60 course of this rocking motion of the lever h^3 , the pin M , which is forced by its spring m^1 against the surface b^{10} of the plate b^9 , primarily travels up the inclined surface b^{12} then, after gliding down across the shoulder b^{13} it is now forced against the inter- 65

mediate step b^{14} and finally, after having slid across the shoulder b^{15} again attains the plane surface b^{10} of the plate b^9 . The arrangement is so devised that in the very instant when the wheel G is exactly positioned 70 above the hollow cylinder C , the pin M will have slid down across the shoulder b^{15} . On the wheel G continuing to run, its flange g^1 travels across the contact face f^5 of the lever F^1 , the hollow cylinder C moving upward again under the action of the spring D , so that accordingly the lever h^3 will now carry out a rocking motion counter to that indicated by arrow z . In the course of this 75 rocking motion, the pin M primarily strikes against the inclined face of the shoulder b^{15} (Fig. 3) and is forced outward in a radial sense conjointly with its bearing body K , this latter, at the same time, displacing itself counter to the action of the spring h^1 80 along the pin h^5 . As the outwardly directed motion of the pin M is initiated, this latter glides across the contact stud b^{17} and in so doing temporarily closes the circuit R^5 r^4 M b^{17} r^{23} r^7 r^{27} r^2 r^3 R^5 (Fig. 11). On 85 its continued return motion the pin M glides along the shoulder b^{15} and the external face of the ledge b^{11} and finally, after the lever h^3 has again attained its initial position, the pin M , acting under the impulse of its spring h^1 , returns into its initial position illustrated. By means of the last-mentioned circuit closing operation the two magnet windings r^7 and r^2 will be excited simultaneously. Now, by the excitation of the magnet winding r^7 , the recording pen S^2 will be forced 90 against the sheet on the drum R , whereas by the excitation of the magnet winding r^2 , the said drum will be rotated forward for a short space. Hence, the straight line r^9 95 will be prolonged for a small extent owing to the pen S constantly bearing up against the drum, while, at the same time, the pen S^2 will mark a line r^{12} at a slight distance remote from the continuous line r^9 but in 100 parallel thereto. The magnet windings r^7 and r^2 ceasing to be excited, the pen S^2 is now again lifted off from the drum R , and this latter stops rotating. Now as soon as, 105 in the further course of the motion executed by the wheel G , its flange g^1 has departed from the contact face f^5 , all the parts resume their initial position illustrated. In the meanwhile, the second wheel of the engine has approached to such an extent, that 110 its flange will commence to press down the hollow cylinder P . As a result, the operation above-explained will come to be repeated, and, since during the depression of the hollow cylinder P , the circuit R^5 r^4 N^6 Q^1 Q N^5 r^4 r^2 r^3 R^5 has been temporarily closed, 115 a brief rotatory motion will be imparted to the drum R and in consequence the straight line r^9 will come to be prolonged for a short section beyond the line r^{12} . The respective 120 125 130

operations will come to suitably repeat themselves when the second wheel of the engine travels across the levers F F¹. The magnet windings r^7 and r^2 will both be simultaneously excited again for a brief space of time, and the pen S² will make a fresh line r^{13} while at the same time the pen S will prolong the straight line r^9 for a corresponding section.

10 The same operations will take place as the third and fourth wheel of the engine travel across the two contact devices arranged on the rail A. In both cases, the straight line r^9 alone will firstly be prolonged for a short section, and then, while continuing line r^9 , there will at the same time be added in succession two new lines r^{14} and r^{15} , respectively, running in the direction of lines r^{12} and r^{13} . Hence, after the engine has travelled across the two contact devices, the recording face of the drum R will contain the four lines r^{12} to r^{15} and the broken line r^8 r^9 which extends exactly to the end of line r^{15} . Now to the rear of the engine there first follow eighteen unloaded axles and then four axles loaded with the maximum weight admissible and which travel with their wheels successively across the two contact devices. The comparatively weak spring p^2 disposed within the pot n^2 will now be compressed by the unloaded axles to the same degree as by the loaded axles, so that the manner of operation of the circuit closing device disposed within the pot n^2 will be exactly the same when an unloaded axle travels across it as when it is traversed by a loaded axle. Hence, the first unloaded axle running across the said circuit closing device likewise causes a short prolongation of the line r^9 . A difference in the manner of operation will, however, occur as soon as the first unloaded axle travels across the circuit closing device of the pot b^3 . For on a wheel of an unloaded axle running across the contact face f^4 of the levers F F¹, the powerful spring D will be compressed to a substantially less extent than when loaded axles travel across it. As a result, the cylinder C will, while the unloaded wheel is at the same time slightly lifted off from the rail A, be moved downwards for a correspondingly smaller measure, and the deflection executed by the lever h^3 will become correspondingly smaller. Now the arrangement is such that in this case the lever h^3 will carry out a deflection of such magnitude that its pin M after travelling up the inclined face b^{12} and sliding down across the shoulder b^{13} will come to a stop on the intermediate step b^{14} .

15 In the course of the upward movement of the cylinder C and the return movement of the lever h^3 , both of which are initiated as the unloaded wheel travels across the contact face f^5 , the lever h^3 will bear up against the shoulder b^{13} and will be shifted radially outwards together with its bearing block K by said shoulder b^{13} , and this counter to the action of the spring h^1 . On this displacement, the pin M comes to glide across the contact stud b^{16} and will, as a result, for a short time 70 cause the circuit R^5 r^4 M b^{16} r^{10} r^6 r^{11} r^4 r^2 r^3 R^5 to be closed. As a result of the circuit having thus been closed, the magnet windings r^3 and r^2 will be simultaneously excited and, in consequence, the recording pen 75 S³ will in this case be forced against the drum R and this latter will itself be fed forward for a short space. The pen S³ will therefore mark a short line r^{16} below line r^9 and in parallel thereto, while at the same 80 time the pen S, which is permanently in the operative position, will prolong said straight line r^9 for a corresponding section. As the following seventeen unloaded axles travel across the cylinders P and C, in exactly the 85 same manner, the line r^9 will each time be firstly prolonged alone for a short space, and then prolonged again, while simultaneously an additional line r^{17} to r^{18} is added in the direction of line r^{16} . The eighteen unloaded 90 axles are succeeded, as said, by four loaded axles of the train travelling across the cylinders P and C. These loaded axles now compress the spring D to such an extent, that the pin M will glide down across the shoulder b^{15} , so that a diagram will be produced 95 on the recording face of the drum R which will resemble that produced by the four-axled engine of the train. Hence, on the four loaded axles travelling across the two 100 devices, there will be caused a corresponding prolongation of the line r^9 and, in addition, above the said line r^9 , four lines r^{19} to r^{20} . Owing to the fact that in the diagram r^9 to r^{20} hitherto produced, the beginning of line r^9 is disposed for a slight measure in front of the commencement of the first line, r^{12} , whereas the end of said line r^9 coincides with the end of the last line, r^{20} , it will be seen that the train first travelled 105 across the cylinder P and then across the cylinder C, that is to say, it has run into the station in the direction indicated by arrow y (Fig. 1).

110 Let it now be assumed that the train lies two hours in the station during which time the empty cars are loaded and the loaded ones discharged, and that then after the engine has first been reversed in the station, the same train now departs, however in the 115 direction opposite to arrow y in Fig. 1. During the time from 2 a. m. to 4 a. m. the screw nut s^1 has shifted itself in the direction of the axis of rotation of the drum R without any rotatory motion having however 120 been imparted to this latter. As a consequence, the pen S will inscribe the straight line r^{21} running in the direction of the axis of rotation of the drum R. At 4 a. m. the four-axled engine followed by four unloaded 125 130

- and eighteen loaded axles will therefore run first across the cylinder C and then across the cylinder P. Hence, the axles of the engine and of the loaded cars will again cause lines r^{22} to r^{28} to be marked and which will be disposed above the continuous straight line r^{23} made by the pen S whereas the unloaded axles cause the lines r^{24} to r^{25} to be marked below the aforesaid line r^{23} . However, in this case, the beginning of the first line, r^{22} , coincides with the commencement of line r^{23} and this for the reason that on the train travelling across the rail in the direction counter to arrow y, the first wheel will primarily run across the cylinder C, so that accordingly the drum R will be rotated while at the same time the pen S^2 is forced against the paper. On the other hand, the end of the continuous line r^{23} projects for a certain measure beyond the end of the last line, r^{26} , for the reason that after the last wheel has run across the cylinder C, it still has to traverse the cylinder P so that the drum R will still be fed forward for a short space. By reason of the fact that in this case again the commencement of the first line, r^{22} , coincides with that of the continuous straight line r^{23} , whereas the end of the last line, r^{26} , remains behind the end of said straight line, it will be clearly ascertained from the diagram that the train has rolled out of the station in a direction counter to that denoted by arrow y.

There is moreover the possibility of so perfecting the described embodiment that the diagram produced will indicate even more refined differences in weight than are presented by loaded and unloaded cars. To this end, it would be necessary to suitably increase the number of the mobile recording pens (S^2 and S^3) and of the appropriate driving devices (contact studs b^{16} b^{17} and electromagnets r^6 r^7). By these means the diagram would then be able to indicate even the precise weight of each axle.

It will thus be seen that the device forming the subject matter of the present invention provides the possibility of watching all the movements of the train as they take place on the section of the track leading to the station, and this both as regards time, direction, number of axles and axle pressure and that it thus offers a safeguard against any unauthorised shunting of empty or loaded cars.

Claims.

1. A recording device for railways comprising electric contact devices positioned adjacent the track rails and adapted to be actuated by the axle pressures of the cars passing over the track, a recording device embodying a movable body and recording members displaceable by a clock mechanism with respect to said body, and electrical circuits including said contact devices and said re-

cording means whereby there will be recorded upon said body the number, running direction, axle pressure and time of the axles travelling across said track.

2. A recording device for railways comprising two electric contact devices positioned adjacent the track rails and adapted to be actuated by different axle pressures of the cars passing over the track, a recording device embodying an intermittently rotatable drum and recording members displaceable by a clock mechanism longitudinally of said drum, and electrical circuits including said contact devices and said recording means whereby there will be recorded upon said drum the number, running direction, axle pressure and time of the axles travelling across said track.

3. A recording device for railways comprising two electric contact devices disposed adjacent the track rail and adapted to be actuated by different axle pressures of the cars passing over the track, a recording device embodying an intermittently rotatable drum carrying a recording sheet and recording members cooperating therewith, means connecting one of said contact devices with said drum for intermittently rotating same, means connecting the other of said contact devices to said recording members and to said drum whereby said drum will be rotated, and said recording members caused to function simultaneously.

4. A recording device for railways comprising two independently operatable contact devices positioned adjacent the track rail and adapted to be actuated by different axle pressures of the cars passing over the track, a recording device embodying a rotatable drum, an electric feed gear for intermittently rotating said drum, three recording members displaceable axially of said drum by a clock mechanism, one of said recording members remaining constantly in contact with said recording drum, an electric circuit including one of said contact devices and electric feed gear, and electric means connecting the other of said contacts with a pair of said recording members and with said electric feed gear, whereby the closing of said last mentioned contact will effect a rotation of said drum and a recording by said recording members of lines serving to indicate the time, the number, and the pressure of axles passing over said track.

5. A recording device for railways comprising two independent electric contact devices positioned adjacent the track rail and adapted to be actuated by different axle pressures of cars passing over the track, a recording device embodying a rotatable drum, electric means for intermittently rotating said drum, three recording members displaceable axially of said drum, a clock work for displacing said recording members.

one of said recording members being disposed so as to constantly remain in contact with said drum, electro-magnets for causing the other two recording members to contact 5 said drum and electric circuits closed by the contact operable by a greater axle pressure for energizing one or the other of said electro-magnets.

6. A recording device for railways comprising

- 10 two independently operable electric contact devices positioned adjacent a track rail and adapted to be actuated by different axle pressure of the cars passing over the track, a recording device embodying
- 15 a rotatable drum, electric magnetic means for intermittently rotating said drum, recording members displaceable axially of said drum, electro-magnets for causing two of said recording members to engage said drum, a
- 20 circuit connecting one of said contact devices with said drum and rotating means, a pair of contacts operable by the other of said contact devices and connected in series with said electro-magnets, said first mentioned circuit being connected in series with said last mentioned circuit.

7. An arrangement of the class described for recording the number, running direction, axle pressure and time of axles travelling 30 across the track of a railway comprising a pair of independently operable contact devices displaceable by the axle pressures of the cars passing over the track, an electrically operated recording device, one of said contact devices embodying two circuit closing elements, a third circuit closing element

resiliently displaceable in an axial and radial direction, means operable by a movable part of said contact device for causing the displacement of said last mentioned circuit 40 closing element, whereby different axial pressures will cause said last mentioned circuit closing element to engage one or the other of said first mentioned circuit closing elements.

8. A recording device for railways comprising two independently operable contact devices positioned adjacent a track rail and adapted to be actuated by different axle pressures of the cars passing over the track, 50 one of said contact devices comprising a stationary and movable part, a pair of circuit closing elements, a third circuit closing element resiliently displaceable in an axial and radial direction, a switch element provided with stepped surfaces for guiding said displaceable circuit closing element, means operable by the movable part of said contact device for rocking said displaceable circuit closing element, a recording device, 55 means for electrically operating said recording device and a circuit including said last mentioned means and said circuit closing elements.

The foregoing specification signed at Es- 65 sen, Germany, this 11th day of December, 1920.

HEINRICH HEYN.

FRIEDRICH ZIMMERMANN.
